WILLIAM MINRATH, OF NEW YORK, N. Y.

MEANS FOR GENERATING COLORED LIGHT FOR ILLUMINATION PURPOSES.

Application filed October 15, 1923. Serial No. 668,577.

My invention relates to the art of illumination, and the object of my invention is to provide means whereby colored light may be generated for advertising purposes or 5 for use on gala occasions. It is also of advantage for use in certain scientific research work.

In carrying out my object I may use a lamp construction as hereinafter set forth, 10 but for many uses I prefer to provide a candle made with the materials combined in such manner as to provide the desired color when burned.

Referring to the drawings which form a 15 part of their specifications:

Figure 1 indicates a candle shown in vertical section.

Figure 2 is a plan view of said candle.

Figure 3 is an illustrational view showing 20 a wick formed in helical shape to provide a greater amount of the chemical used to generate the color in a candle of a given length.

Figure 4 illustrates the wick which may be made and sold as a separate article of manu- 25 facture.

Figure 5 is a vertical sectional view of a lamp illustrating the use of the wick when used with oil, etc.

A, indicates a wick made of cotton or 30 other suitable material such as usually found in ordinary candles.

B, indicates a coating or envelope of wax or paraffine.

C, indicates a body portion of combustible 35 material such as wax or paraffine.

In providing the wicks I use certain chemicals depending upon the color to be generated when the candle is burned.

To generate a red color I prefer to use 40 strontium chlorate and for a green color barium chlorate, which I have found to be much superior to other salts which I have tried. Both of these salts are soluble in water and I therefore make a saturated solution of the desired salt and then soak the wicking therein and allow it to dry thus causing the crystals of the salt to form in the wick.

I also prepare some wax or paraffine and 50 melt the same and then add the salt thereto to provide a paste rich in the chemicals and while still warm I cover the wicking with a coating of this paste. I then cut the

wicking into the lengths corresponding to the length of the candle to be made, or slightly longer, and pack them in boxes for sale. 55

To make the complete candles, I take the wicks as above finished, and mold the body portion of wax or paraffin around each wick in the usual manner of making wax candles. 60

In Figure 3 I have shown the wick made in the form of a helix to provide a greater amount of the chemical, thereby generating a more intense or deeper color in the flame of the candle. 65

In Figure 5 I illustrate a simple lamp construction in which E indicates the receptacle for oil, D the oil therein, and F a holder to support the wick A, the cup F' serving to hold any overflow or dripping of 70 oil.

It is obvious that a mixture of barium and strontium could be used instead of either of said salts separately to provide a colored light and that other such salts or suitable 75 compounds may be used to provide light of many different colors and shades of color.

Having thus described my invention I claim as new:—

1. An article of manufacture comprising 80 a cellulose wick impregnated with a chlorate salt solution crystallizable upon drying and when ignited producing a colored flame.

2. An article of manufacture comprising 85 a cellulose lamp wick impregnated with a chlorate salt solution crystallizable upon drying and forming a coating on the wick to produce a colored flame when ignited.

3. A color emitting candle comprising an 90 inflammable body, a wick embedded in said body, said wick being impregnated with a chlorate salt solution crystallizable upon drying.

4. A color emitting candle comprising an 95 inflammable body, a helical formed wick in said body, said wick being impregnated with a chlorate salt solution crystallizable interiorly and exteriorly of said wick upon drying.

5. The process of making a wick to provide colored light consisting in dipping a wick into a chlorate salt solution, then drying the wick to cause said salt to crystallize in the wick, then coating said wick with com- 100 bustible material. 105

6. The process of making a wick to provide a colored light which consists in dipping a wick into a chlorate salt solution, drying the wick to cause the salt to crystallize and then coating the wick with a combustible paste containing a quantity of the said salt solution. 15
7. The process of making a wick to provide a colored light which consists in dipping a wick into a chlorate salt solution 10
- which may have as its characteristic element either barium or strontium, drying the wick to cause the salt to crystallize and then coating the said wick with a combustible paste containing a quantity of the said solution.

In testimony whereof, WILLIAM MINRATH has signed his name to this specification this second day of October, 1923.

WILLIAM MINRATH.
